UNITED STATES PATENT OFFICE.

JOSEPH D. KILGORE, OF COLUMBUS, OHIO, ASSIGNOR TO KILGORE FOUNDRY CO., OF COLUMBUS, OHIO, A CORPORATION OF OHIO.

TOY PISTOL.

Application filed June 29, 1927. Serial No. 202,290.

My invention relates to a toy pistol.

The general object of my invention is to provide a pistol improved in various particulars, especially with respect to means 5 on the hammer to prevent the products of the explosion, when a cap is fired, from injuring the user of the pistol, and also to insure precision and effectiveness in the means for feeding the cap strip.

10 The nature of my invention and its distinguishing features and advantages will clearly appear as the description proceeds.

Reference is to be had to the accompanying drawings, forming part of this specification, it being understood that the drawings are merely illustrative of one example 15 of the invention.

Figure 1 is a side elevation of a pistol with part of its inner side broken away to 20 expose the interior.

Figure 2 is a plan view of the barrel and a portion of the strip chamber, half in section.

Figure 3 is a perspective view of the 25 hammer.

In carrying out my invention in accordance with the illustrated example the pistol handle 10 is connected with a hammer 11 having an upwardly extending nose 12 adjacent to which is a formation at the top representing a sight. The forward extension or nose 12 extends forwardly to overlap the chamber 15 through which the cap strip passes to extend along back of said 30 chamber 15 so that the hammer 11 will explode the cap against said back of said chamber. The forward extension 12 overlapping the chamber 15 prevents fire flash backward.

40 The numeral 14 indicates the cap strip extending along the back of chamber 15 and 114 indicates the roll of the cap strip. The numeral 16 indicates the trigger of the pistol, 17 a pawl controlling the hammer 11, said 45 pawl being pivoted at one end as at 18 to trigger 16 and pivoted as at 21 to a feed pawl 22 for feeding the cap strip 14. That end of the pawl 19 engaging hammer 11 is received in a notch 20 in said hammer. The 50 feed pawl 22 for the feed strip 14 is limited in one direction by stop 23. The numeral 24 indicates a spring for the trigger 16, 55 25 a spring for the pawl 17 and having a coil 26 about the pin forming the pivot 21, said spring 25 having that terminal re-

mote from trigger 16 engaged in a notch 27 on feed pawl 22.

The described formation of the hammer by receiving the upper rear angle of the cap chamber 15 and overlapping at the 60 top prevents injury from explosion of the cap. The assemblage of the pawl 17 and feed pawl 22 leaves said feed pawl free to function effectively unaffected by the other elements of the assemblage.

65 The usual gate provided at one side of toy pistols of the type to which the invention relates for affording access to the roll of caps 114, is designated in the drawing by the numeral 28 and as it corresponds 70 with the known form of gate will be readily understood in the art without further reference thereto. Spring means have been provided for holding the gate 28 in closed or open position by bearing against the cam 75 flange 29. In accordance with my invention I provide a novel gate and spring assemblage. A plate spring 30 is provided having a U-shaped bent end 31 which end is held in a depression 32 in a transverse rib 33 on 80 one side of the pistol. A coating rib 34 is provided on the opposite side of the pistol and in the plane of the rib 33 so that the U-shaped end 31 of the spring 30 is held between the ribs 33 and 34 and restrained against displacement. The spring 30 is inclined from the U-shaped end 31 toward the opposite side of the pistol and bears against said opposite side as at 35. The arrangement is such that the spring 90 30 is slightly bowed and stressed by the cam flange 29 of the gate 28. Hence said gate can be swung into the closed position shown in Figure 2 or at 90° to such position to expose the roll 114. In both positions of 95 the gate 28 the pressure of the spring 30 against the flange 29 holds the gate in position.

I would state furthermore that while the 100 illustrated example constitutes a practical embodiment of my invention, I do not limit myself strictly to the exact details herein illustrated since, manifestly, the same can be considerably varied without departure from the spirit of the invention as defined 105 in the appended claims.

What I claim is:

1. In a toy pistol a hammer, a trigger, a pawl pivoted at one end to said trigger and having its opposite end engaging in a 110

notch in the hammer, a chamber to receive a cap strip roll and a feed pawl pivoted to said first mentioned pawl between the ends of the latter and adapted to feed 5 said cap strip to the hammer; together with a spring acting on said trigger, said spring having a member coiled about the pivot of the first mentioned pawl and terminating in an arm engaging the second mentioned 10 pawl.

2. In a toy pistol a gate swingable at one side of said pistol, a spring within the pistol having a portion bearing against the gate to hold it in either the open or closed position, said spring having a U-shaped bent 15 end, and ribs on the opposite sides of the pistol between which the said U-shaped end of the spring is held.

JOSEPH D. KILGORE.
